CLAIM

The ornamental design for a butler table, as shown and
described.

DESCRIPTION

FIG. 1 is a perspective view of a butler table, showing
my new design;

FIG. 2 is a top plan view thereof;

FIG. 3 is a side elevational view thereof;

FIG. 4 is a bottom plan view thereof;

FIG. 5 is a perspective view of a butler table, showing
a second embodiment of my new design;

FIG. 6 is a side elevational view thereof;

FIG. 7 is a perspective view of a butler table, showing
a third embodiment of my new design; and,

FIG. 8 is a side elevational view thereof.
